(57) **CLAIM**

The ornamental design for a kart with movable visual effect, as shown and described.

DESCRIPTION

FIG. 1 is a front perspective view of a kart with movable visual effect.

FIG. 2 is a rear perspective view of the kart of FIG. 1.

FIG. 3 is a front view of the kart of FIG. 1.

FIG. 4 is a rear view of the kart of FIG. 1.

FIG. 5 is a left side view of the kart of FIG. 1.

FIG. 6 is a right side view of the kart of FIG. 1.

FIG. 7 is a top view of the kart of FIG. 1.

FIG. 8 is a bottom view of the kart of FIG. 1.

FIG. 9 illustrates a head portion of the kart of FIG. 1 in a first state with the eyes in a first position relative to the openings in the head corresponding to a first position of the steering arm relative to the body. The eyes of the inner member include an outer portion or sclera, a ring portion or iris and an inner portion or pupil.

FIG. 10 illustrates the head portion of the kart of FIG. 9 in a second state with the eyes in a second position relative to the openings in the head corresponding to a second position of the steering arm relative to the body turned toward the right side relative to the position of FIG. 9.

FIG. 11 illustrates the head portion of the kart of FIG. 9 in a third state with the eyes in a third position relative to the openings in the head corresponding to a third position of the steering arm relative to the body turned back toward the center relative to the position of FIG. 10. The third position of FIG. 11 can be the same as the first position of FIG. 9; and,

FIG. 12 illustrates the head portion of the kart of FIG. 9 in a fourth state with the eyes in a fourth position relative to the openings in the head corresponding to a fourth position of the steering arm relative to the body turned toward the left side relative to the position of FIG. 11. The four discrete positions illustrated represent movement of the inner member and eyes relative to the outer member or head along with steering movement of the steering arm.

FIGS. 9-12 are shown separately for ease and clarity of illustration.

Portions of the kart shown in broken lines form no part of the claimed design.

1 Claim, 6 Drawing Sheets
